UNITED STATES PATENT OFFICE.

ARTHUR PRIMROSE YOUNG, OF KENILWORTH, ENGLAND, ASSIGNEE TO GENERAL ELECTRIC COMPANY, A CORPORATION OF NEW YORK.

TELEPHONE RECEIVER.

Application filed April 14, 1925, Serial No. 22,973, and in Great Britain April 17, 1924.

My present invention relates to electro-magnetic instruments of the type having a magnetic circuit comprising a permanent magnet, attached to the ends of which are 5 pole pieces, and particularly to telephone receivers or transmitters for use in connection with wireless or ordinary telephony or telegraphy. Devices of this type have been disclosed in my copending application, Serial 10 No. 640,060, filed May 19, 1923, of which this application is a continuation in part.

The invention consists in so forming each pole piece that at its junction with the permanent magnet it embraces the end of the 15 magnet and makes a close fit therewith. Each pole piece may be formed from a soft iron strip and bent to shape and finally pressed on to the end of the magnet in a press. Alternatively two pole pieces with 20 a connecting strip of metal may be stamped out of a plate or ordinary dynamo iron, a number of the stampings riveted together, the magnet fitted into place and then the connecting strip machined away. The 25 assembly of pole pieces and magnet made by either of the above methods may then be mounted in a casing or moulded into a composite insulating material, such for instance as synthetic resin, which also forms the body 30 and casing of the instrument.

The novel features which I believe to be characteristic of my invention are set forth with particularity in the appended claims.

My invention itself, however, both as to its 35 organization and method of operation will best be understood by reference to the following description taken in connection with the accompanying drawing in which Fig. 1 shows a side view of the assembled pole 40 pieces and magnet; Fig. 2 is a side view of a modification; and Fig. 3 is a cross sectional view of a telephone receiver embodying my invention, certain parts of the receiver being omitted in the interest of clear- 45 ness.

With reference to the drawing, the magnetic circuit includes an approximately L-shaped pole piece, having one limb bent round substantially through 180° away from the other limb. The resulting shape is like a U 13 having unequal parallel arms 14 and 50 15, and the coil limb 12 projecting at substantially right angles from the end of the arm 15; or like a letter U on its side with the end of one limb joined to the horizontal 55

limb of a letter L. The permanent magnet 16 may be a flat bar as here shown or of curved pattern, and it is arranged with its polar extremities projecting into the U-shaped hollows 17 of each pole piece. 60

According to one method of carrying out the invention as illustrated in Fig. 1, a flat strip of soft iron is bent into the shape previously described. A small slot, not shown, may be provided at the base of the U-shaped portion 13 to facilitate bending, and the arm 15 of the U-shaped portion may be curved at its extremity away from the other arm 14 as shown at 18, in order that the base of the limb 12 may be raised substantially 70 clear of the surface of the magnet 16 so as to utilize as much as possible of the length of the magnet and to provide a suitable seating for the coil. In the preferred construction, a short flat bar magnet of cobalt 75 steel is placed with its ends projecting into the hollows of the U-shaped portions 13, the width of the magnet being substantially equal to the width of the pole pieces at each end. The ends of the magnet are preferably made rough or provided with recesses so that the soft iron of the pole pieces will 80 adhere firmly thereto. The parts are then placed in a jig and pressed firmly together. The whole may then be placed together with 85 a composite insulating material in the interior of a mould and the composite insulating material may be moulded to secure the magnetic structure into position in a casing or itself moulded to form the body and cas- 90 ing of the instrument.

According to another method of carrying the invention into effect as applied to a watch type telephone receiver, as is illustrated in Figs. 2 and 3, stampings of a thickness say, of .04 inch, are made of the shape above described but with an integral connecting strip of metal 19 joining the ends of the pole pieces where in contact with the magnet. When the magnet is in place this 100 connecting strip is preferably spaced away from the magnet, i. e. by the provision of a recess 20, so that it can be easily machined away subsequently without damaging the magnet. These stampings are riveted together in sufficient number to form a suitable width of pole piece and the permanent magnet is then pressed into place, the stampings being of such dimensions that at the 105 ends of the magnet a tight fit is secured. 110

After milling away the strip connecting the pole pieces the magnetic structure is ready for mounting or moulding as above described. In the drawing the composite insulating material is shown moulded into the casing 21. This method of forming the pole pieces has the advantage that the correct spacing of the coil limbs 12 from one another and from the magnet is secured automatically.

The magnet in either case may be magnetized either before or after assembly.

What I claim as new and desire to secure by Letters Patent of the United States, is:

- 15 1. A telephone receiver or like device comprising a flat bar permanent magnet and a pole piece embracing one end of said magnet and in contact with the end surface thereof.
- 20 2. A telephone receiver or like device comprising a flat bar permanent magnet, a pole piece embracing each end of said magnet, said pole piece comprising two portions adjacent and substantially parallel to one another and a third portion perpendicular to said parallel portions and adapted to support a winding.
- 25

3. A telephone receiver or like device comprising a flat bar permanent magnet, a bent pole piece embracing one end of said magnet and in contact with the end surface thereof, said magnet and a portion of said pole piece being embedded in insulating material.

4. A telephone receiver or like device comprising a permanent bar magnet, a pole piece closely embracing one end of said magnet 35 and having a portion substantially parallel to but spaced from said magnet, and a second portion substantially perpendicular to said parallel portion and adapted to support a winding.

5. A telephone receiver or like device comprising a flat bar permanent magnet, a bent pole piece embracing one end of said magnet and in contact with the end surface thereof, said pole piece having a portion 45 spaced from but substantially parallel to said magnet, said magnet and a portion of said pole piece being embedded in insulating material.

In witness whereof, I have hereunto set my hand this 20th day of March, 1925.

ARTHUR PRIMROSE YOUNG.
